UNITED STATES PATENT OFFICE.

MATTHEW C. CARSWELL, OF BROOKLYN, NEW YORK.

MOVABLE PLATFORM FOR RAILWAY-STATIONS, &c.

SPECIFICATION forming part of Letters Patent No. 350,232, dated October 5, 1886.

Application filed February 13, 1886. Serial No. 191,792. (No model.)

To all whom it may concern:

Be it known that I, MATTHEW C. CARSWELL, of Brooklyn, in the county of Kings and State of New York, have invented a new and useful Improvement in Movable Platforms for Railway-Stations and other Purposes, of which the following is a specification.

On elevated railways the station-platforms are sometimes required to be arranged at a curved portion of the track, and in such case the station-platform itself is curved correspondingly to the track. When cars are stopped at the station-platform, they will be approximately tangential to the curve thereof, and even if the sides of the cars come close to the edge of the platform at the middle of the length of the car the car-platforms will be considerably removed from the edge of the station-platform, and accidents have been frequent by reason of persons falling or slipping down between the station-platform and the car-platforms.

An important object of my invention is to provide for bridging over or covering the space between the car-platforms and the curved platform of an elevated railway-station; but the invention is also applicable to other stationary platforms—such as wharves or docks—and the street-platforms of stores or warehouses.

The invention consists, essentially, in the combination, with a fixed platform, of a supplemental platform arranged beneath the fixed platform and movable inward and outward relatively thereto, so that the supplemental platform may project beyond the fixed platform, or be drawn inward and sheathed or concealed beneath the fixed platform.

The invention also consists in the combination, with a curved station-platform and a curved railway-track adjacent thereto, of a supplemental platform movable inward and outward relatively to the station-platform for bridging over the space between the station-platform and platform of a car. The movable platform, or any number of them, may be operated by a hand-lever and suitable rods or connections, and a spring may be likewise employed, if desired, in order to project the movable platform outward from the fixed plat-

form, or to aid in moving it outward from the fixed platform. In an elevated-railway platform the movable supplemental platform will be provided with rods or bars which are guided in the stringers or floor-beams of the fixed station-platform. 55

In the accompanying drawings, Figure 1 is a plan of a curved station-platform and a railway-track, and cars adjacent thereto, a portion of the flooring of the station-platform being removed to show the arrangement of the movable platform. Fig. 2 is a side elevation of the track and station-platform, and Fig. 3 is a transverse section of the fixed and movable station-platforms upon a larger scale. 65

Similar letters of reference designate corresponding parts in the several figures.

A designates the fixed and curved station-platform, the planks or floor-boards of which are supported on floor beams or stringers A', and B designates a curved railway-track adjacent thereto. 70

C designates the cars of the train on the track, and it will be readily understood that as the straight sides are approximately tangential to the curve of the track and platform the platforms or ends of the cars will be considerably removed from the edge of the curved station-platform, even though the middle of the car comes close to the edge of the platform. 75

To bridge over or cover the space between the stationary platform A and the platform of the car, I employ supplemental platforms D, two of which are here represented. These supplemental platforms are movable inward and outward relatively to the fixed platform A, and their outer edges are beveled, so that they will approximately fit against the sides of the cars at the ends thereof. 85

As here represented, the movable platforms have bars or rods d, which project inward from them and are guided in the floor beams or stringers A' of the station-platform A, the floor beams or stringers being notched or recessed to receive said bars or rods, and the platform may be slotted, as represented at d*, so as to receive pins or bolts e, which limit the movement of the platform inward and outward, as best shown in Fig. 3. If desired, a 95 100

spring, *f*, may be applied to one of the bars or rods *d*, as best shown in Fig. 3, in order to project the movable or supplemental platform *D* outward from the main fixed platform *A*, or 5 to aid in producing such outward movement of the supplemental platform.

In order to move the movable platform *D* positively, I have represented a hand-lever, *g*, which, by rods *g'*, is connected with bell-crank 10 levers *g''*, one arm of each bell-crank lever *g''* having connected with it a rod, *g'*, and the other arm of each bell-crank lever *g''* having a connection with one of the bars or rods *d* of the supplemental or movable platform. In this 15 way any desired number of supplemental platforms may be moved inward and outward relatively to the fixed platform by means of a single hand-lever and connections suitably arranged between the hand-lever and the supplemental or movable platforms.

The supplemental or movable platforms *D* should not project sufficiently beyond the fixed platform to cause the cars to strike full against their edges, and the outer edges of these supplemental platforms are beveled, as described, 25 so that the cars, by acting on their beveled edges, may push them inward if they have too great projection.

The supplemental or movable platforms 30 provide for bridging the space between the station or fixed platform *A* and the platforms of the cars *C*, and prevent any accident from persons slipping or falling through the space between the fixed platform and the car-platforms. The supplemental or movable platforms slide inward and outward beneath the 35 fixed stationary platform *A*, and when moved inward they are sheathed beneath the fixed platform and no person can trip on their edges 40 and fall.

The beveled outer edge of the movable platforms *D* may be provided with anti-friction rollers *s*, to prevent any injury to the car from rubbing on the platform.

45 What I claim as my invention, and desire to secure by Letters Patent, is—

1. The combination, with a fixed platform, of a supplemental platform arranged beneath the fixed platform, and movable inward and outward relatively thereto, substantially as 50 herein described.

2. The combination, with a curved station-platform and a curved railway-track adjacent thereto, of a supplemental platform movable inward and outward relatively to the station-platform for bridging the space between the station-platform and the platform of a car, substantially as herein described. 55

3. The combination, with a fixed platform, of a supplemental platform movable inward 60 and outward relatively to the fixed platform, and a lever and connections whereby said supplemental platform may be operated, substantially as herein described.

4. The combination, with a fixed platform, 65 of a supplemental platform movable inward and outward relatively to the fixed platform, and a spring for projecting the movable platform beyond the fixed platform, substantially as herein described.

5. The combination, with a fixed and curved station-platform and a curved railway-track, 70 of a supplemental platform movable inward and outward relatively to the fixed platform, and rods or bars supporting the supplemental platform and guided in the stringers or floor-beams of the stationary platform, substantially as herein described.

6. The combination, with a fixed and curved station-platform and a curved railway-track 75 adjacent thereto, of a number of supplemental platforms, movable toward and from the fixed platform for bridging over the space between the station-platform and the car-platforms, and a hand-lever and connections whereby the supplemental platforms may be operated, substantially as herein described. 80
